MODULATION

Werner Buschbeck, Berlin, Germany, assignor to
 Telefunken Gesellschaft für Drahtlose Tele-
 graphie m. b. H., Berlin, Germany, a corpora-
 tion of Germany

Application February 18, 1933, Serial No. 657,377
 In Germany March 11, 1932

3 Claims. (Cl. 179—171)

This invention relates to a method of modulation and a modulation circuit scheme.

It is well known that the grid direct current of thermionic tubes bears no linear relation to the grid voltage. Now, in order that this condition which is undesirable with a view to insure linear modulation curves in modulation methods based upon grid action may be minimized as much as possible, it is known from the prior art that auxiliary direct current may be added to the grid direct current; and if the former be chosen sufficiently large is able to reduce the non-linear influences of the grid direct current to any desired degree.

5

10 In describing the invention reference will be made to the drawing in which Figure 1 shows a circuit arranged in accordance with the present invention, while Figures 2, 3 and 4 show modifications of the arrangement of Figure 1.

15 In Figure 1, H is the main transmitter valve, M the modulator tube, E_z the source for the additional direct current which flows by way of resistance R_z between the anode and cathode of M, V a grid biasing battery to maintain the grid 20 of the modulator tube at the desired negative potential. It will be understood that a large additional direct current requires a larger number of modulator tubes as well as a supplemental electromotive force of greater value.

25 Now, according to the present invention the identical result is to be obtained with essentially smaller expenditures in that the grid biasing potential of the modulator tubes is derived from the fall of potential caused by the supplemental direct current I_z between the anode and cathode of M, across the resistance R_z (Figure 2) rather than being supplied, according to prior practice, from a fixed electromotive force. Several voltages are active across the terminals of resistance 30 R_z . The potential drop in R_z due to the current caused by the additional electromotive force E_z to flow in the anode to cathode circuit of M is added to the voltage E_R set up across the impedance of the modulator tube M by the current I_g , which flows between the cathode and grid of tube H due to grid rectification. These 35 voltage drops are in parallel between the control grid and cathode of tube H as clearly shown. The algebraic sum of these voltages is applied 40 between the control grid and cathode of tube H to determine the grid bias thereof. Now, if the grid direct current due to grid rectification rises more markedly than linearly, then the 45 voltage E_R across the modulator tube impedance

increases more strongly than linearly also. This voltage opposes the supplemental voltage E_z and causes the supplemental direct current to fall off faster than linearly and thus also causes the voltage across the modulator tube to decrease faster than linearly, the resistance of the latter decreasing more rapidly than linearly with the consequence that the effect of non-linear current due to grid rectification is counteracted. At the same time, by the arrangement to be 10 chosen according to the invention, a distinct grid biasing electromotive force for the modulator tube may be dispensed with.

5

In order that the size of the compensating actions may be rendered independent of the grid biasing voltage, it will be feasible to provide in series with the grid tap a distinct electromotive force B (Figure 3) which for modulation purposes, i. e., for dynamic actions may be replaced also by a double tap B1, B2 (Figure 4) by way 20 of impedances being in one case permeable for alternating and in the other for direct current voltages.

Having thus described my invention, what I claim is:

1. A thermionic relay having control grid and cathode connected to a source of carrier waves to be modulated and an output electrode connected with a work circuit, and a circuit for modulating the carrier waves from said source in said relay, 30 said circuit including means for insuring said modulation of said carrier is linear with respect to the modulating potentials comprising, a modulator tube having anode, cathode and control grid, a connection between the cathode of said modulator tube and the control grid of said thermionic relay, a connection between the anode of said modulator tube and the cathode of said thermionic relay, a resistance and a source of potential connected between the anode and cathode of said modulator tube, a source of modulating potential, a transformer having a primary winding connected to said source of modulating potential and a secondary winding connected between a movable point on said resistance and the 35 control grid of said modulator tube.

2. A device as recited in claim 1, in which a resistance is connected in series with said secondary winding.

3. A device as recited in claim 1, in which a 50 resistance shunted by a condenser is connected in series with said secondary winding.

WERNER BUSCHBECK.
